EARRING

Louis C. Mark, Cranston, R. I.

Application January 29, 1943, Serial No. 473,935

1 Claim. (Cl. 63—14)

My present invention relates to the jewelry art and has particular reference to a novel construction of earring.

The principal object of the present invention is to provide an earring having a spring snap retaining member which will retain its resiliency for a considerable period of time.

Another object of the present invention is to provide an earring which is simple in construction and easy and economical to manufacture and assemble.

With the above and other objects and advantageous features in view, my invention consists of a novel arrangement of parts, more fully described in the detailed description following, and more particularly defined in the appended claim.

In the drawing,

Fig. 1 is a perspective view of an earring embodying my invention;

Fig. 2 is a perspective view of the spring tongue;

Fig. 3 is a perspective view of the hinge piece;

Fig. 4 is an enlarged section of the earring with the closure snap in closed position; and

Fig. 5 is a similar view in open position.

In the manufacture of earrings of the non-piercing type, it is necessary to provide a snap or spring jaw of sufficient resilient tension to hold the earring on the ear. Many of the devices now in use have a tendency to lose their resiliency after a period of use. The present invention is designed to overcome this difficulty and to provide a device which is simple and easy to manufacture and assemble and which will retain its strong spring action indefinitely.

Referring more in detail to the drawing illustrating my invention, I have shown an earring 10 having an ornamental portion 11 in the form of an L-shaped shank 12, setting 13, and ornamental pearl 14. Any type of ornament may be employed, and the construction of the ornamental portion may be varied to suit the requirements for different earrings.

To retain the earring on the ear, I provide the inner or rear leg of the L-shaped shank 12 with

an integral looped portion 15 which forms a bearing for the hinge pin 16 extending therethrough. A hinged member 17, Fig. 3, is provided at one end with ears 18 having journal openings to receive the pin 16. The member 17 is generally rectangular in shape, flaring outwardly towards its free end 19, which is angularly bent, so that in locking position, Figs. 1 and 4, its edge will bear against the rear of the ornamental portion (or the inserted ear). A spring tongue 20, Fig. 2, having a tapered shank 21 and a reentrantly bent end 22, is positioned over the member 17 as shown in Figs. 1 and 4. The reentrantly bent portion 22 is slipped over the bent end 19 of the member 17 and pinched thereon.

In this position, the shank 21 of the spring tongue bears against the edge 23 of the member 12. The edge 23 acts as a cam edge, and the members 17 and 12 are resiliently retained in the closed, Fig. 4, and open, Fig. 5, positions thereby, swinging from one to the other with a snap action.

By making the tongue 20 of a separate piece, its resiliency can be increased by the use of a heavier spring metal, the pinched end adding to the resiliency and its life.

While I have described a specific constructional embodiment of my invention, it is obvious that changes may be made in the size, shape, and relative arrangement of parts, without departing from the spirit and scope of the invention as defined in the appended claim.

I claim:

An earring comprising an ornamental portion having a loop, a pivot pin extending through said loop, a pivot member having ears pivoted on said pin, the free end of said pivot member being angularly bent, and a spring tongue positioned over said pivot member, said spring tongue having a reentrantly bent end pinched over the angularly bent end of said pivot member, and said spring tongue having a shank portion bearing against the loop portion to provide a resilient snap action.

LOUIS C. MARK.
